GARMENT

**Abram K. Baer, Baltimore, Md., assignor to The
Strouse-Baer Company, Baltimore, Md.**

Application August 27, 1937, Serial No. 161,333

1 Claim. (Cl. 2—237)

This invention relates to a garment for men's, women's, and children's wear but more particularly to an outer wear garment of the waistband type.

5 The invention has for its object to provide, in a manner as hereinafter set forth a garment so constructed, whereby when it is worn it will snugly hug the waist of the body of the wearer for suspending it without disturbing the appearance of the garment and at the same time maintain the front of the waistband smooth and flat without discomfiture to the wearer.

15 A further object of the invention is to provide, in a manner as hereinafter set forth, a garment of the type referred to including a snug fitting suspension therefor so constructed and arranged to not only satisfactorily suspend, but also to enhance the appearance of the garment at the front of its waistband.

20 A further object of the invention is to provide, in a manner as hereinafter set forth, a garment of the type referred to including as a part thereof a yieldable suspension therefor, of a form which dispenses with the use of a belt slidably coupled 25 to the waistband for binding the latter to the waist of the wearer to suspend the garment.

A further object of the invention is to provide, in a manner as hereinafter set forth, a garment of the type referred to including a satisfactory 30 suspension therefor so formed and arranged to permit of the free breathing of the wearer when the garment is worn and in snug engagement with the waist of the wearer.

35 A further object of the invention is to provide
in a manner as hereinafter set forth, a garment
of the type referred to including an internally
arranged elastic suspension element therefor, at-
tached at its ends to the waistband at two spaced
points of the inner face of the front of the latter
40 and attached intermediate its ends to the inner
face of the back of the waistband.

Further objects of the invention are to provide, in a manner as hereinafter set forth, a garment of the class referred to which is simple in its construction, strong, durable, compact, readily assembled, thoroughly efficient for the purpose intended thereby, and comparatively inexpensive to manufacture.

To the above ends essentially and to others
50 which may hereinafter appear, the invention con-
sists of the novel construction, combination and
arrangement of parts as will be more specifically
described and illustrated in the accompanying
drawing wherein is shown an embodiment of the
55 invention, but it is to be understood that changes,

variations and modifications may be resorted to which fall within the scope of the invention as claimed.

The garment is illustrated by way of example as a pair of shorts, but it is to be understood that it is not limited to such form as it relates to any type of garment having a waistband at its top or bottom. 5

In the drawing:—

Figure 1 is a front elevation of a garment, in accordance with this invention with the suspension element thereof in non-extended position,

Figure 2 is a fragmentary view in perspective of the upper portion of the garment, looking towards its front and with the suspension element 15 thereof in extended position,

Figure 3 is a fragmentary view in perspective of the upper portion of the garment looking towards its back and with the suspension element thereof in non-extended position, and

Figure 4 is an elevation of the suspension element looking towards its rear.

The garment as illustrated is what is termed a pair of shorts, is generally indicated at 5 and includes a body part 6 which is provided at its top with a waistband 7 and has depending from its bottom a pair of legs 8, 9. 25

The waistband 7 centrally of its back 10 is formed with a button hole 11 and its sides 13, 14 with button holes 15, 16 respectively. The button holes 11, 15, 16 are disposed lengthwise and preferably on the longitudinal median of the waistband.

Arranged within the top of the garment and opposing the inner face of the waistband 7 is an elastic suspension element 17 of strap-like form having its body preferably of a width less than that of the body of waistband 7 and is so shown. The lower lengthwise edge of element 17 aligns with the bottom, its upper lengthwise edge is positioned below the top and its length is materially less than that of waistband 7.

The element 17 consists of a single length of elastic tape 18 having its end terminal portions inturned or reverted to form folds 19, 20 positioned against the rear face of the tape. Arranged against the rear face of the tape 18, at the transverse center thereof is a button 21 which is anchored to element 17 by the sewing 22. The button 21 coacts with the button hole 50 11 for connecting the back of element 17 to the back 10 of the waistband 7. Positioned against the outer faces of the folds 19, 20 are buttons 22, 23 which are anchored to element 17 by the sewing 24, 25 respectively. The sewing 24, 25 55

also anchors the folds 19, 20 respectively against the rear face of the tape. When the folds 19, 20 are anchored they provide for reinforcing the ends of the element 17, as well as form cushions 5 for the buttons 22, 23 when the buttons tend to move inwardly or shifted rearwardly at an inclination to the horizontal on the application of pressure to the ends of element 17. The central part of the back portion of element 17 constitutes a cushion for button 21 when pressure is applied to the latter. The buttons 22, 23 coact with the button holes 15, 16 respectively for connecting the ends of the element 17 to the points of emergence of the front 12 of the waistband 15 7 with the sides 13, 14 of the latter. The length of that portion 26 of element 17 extending from button hole 11 to button hole 15 is materially less than that portion of the waistband extending from button hole 15 to button hole 11. The 10 length of that portion 27 of element 17 extending from button hole 11 to button hole 16 is materially less than that portion of the waistband extending from button hole 16 to button hole 11. The 15 portions 26, 27 of element 17 are of like length and when extended will be positioned against the inner faces of the sides and back of the waistband. The latter conceals the element 17. The lower part 28 of element 27 is transversely corrugated and its upper part 29 is length- 20 wisely corrugated whereby said lower part 28 is more freely elastic and pliable than said upper part 29. When the garment is worn the element 17 will be extended to yieldingly and snugly engage the back and sides of the waist of the wearer and act as a suspension for and to hold the garment up. The extension of element 17 will not 25 in any manner disturb the appearance of the garment and at the same time permanently maintain the front of the waistband smooth, flat, and ungathered whereby the appearance of such front is enhanced as the button 21 is on the rear face of the tape 18 and the buttons 22, 23 on the outer faces of the folds, the inner surface of ele- 30

ment 17 between the bends of the folds will be uninterrupted whereby, when element 17 is worn and extended no discomfiture from buttons bearing on the wearer is present.

The construction of the garment will provide for it to snugly fit around the waist thereby eliminating all possibility of the garment dropping down and at the same time doing away with the unsightliness caused by the pulling of a belt tight, as well as the overcoming objection of a tight belt preventing free breathing due to the binding of the waist band against the wearer. 5

What I claim is:—

A garment including a body portion formed at its top with a waist band, said waste band at 15 each end of its front portion and centrally of its back portion being provided with a button hole; a continuous one-piece band elastic from end to end arranged to oppose the major portion of the inner face of the waist band, said elastic band having its end terminal portions reverted against its outer side to form folds for reinforcing the ends of such band, a button secured to the elastic band and positioned against the outer surface of and cushioned by each reverted end terminal portion and a button secured to the transverse median of the outer side of and cushioned by the elastic band whereby the latter will be provided, between the bends of the folds with an uninterrupted surface on its inner side, said buttons coacting with said button holes for detachably connecting the elastic band to the waist band, and said elastic band when formed with the reverted end terminal portions and connected to the waist band having its length less than the 20 combined length of the back and side portions of the waist band disposed between the front button holes whereby the elastic band, when the garment is worn, will be longitudinally stretched for holding the garment in position on the wearer 25 and will bear on the inner faces of the said back and side portions. 30
